UNITED STATES PATENT OFFICE.

THOMAS MALCOLM McALPINE, OF WESTMINSTER, LONDON, ENGLAND.

TUNNELING.

1,242,217.

Specification of Letters Patent.

Patented Oct. 9, 1917.

Application filed June 20, 1917. Serial No. 175,933.

To all whom it may concern:

Be it known that I, THOMAS MALCOLM McALPINE, subject of the King of Great Britain, residing at No. 2 Central Buildings, 5 Westminster, in the county of London, England, have invented new and useful Improvements Relating to Tunneling, of which the following is a specification.

This invention relates to a method of constructing large tunnels and its object is to enable such tunnels to be constructed with greater facility and at less cost than hitherto.

The invention consists broadly in excavating separated sections of the tunnel at intervals around the arch of the tunnel and filling with concrete or other material suitable for forming the supporting arch the excavations or portions of the excavations 15 to be occupied by the corresponding portions of the arch, and then similarly excavating and filling in with concrete or other suitable material the sections between the spaces previously filled in, prior to the removal of the natural core or "dumpling" 20 which occupies the interior of the space covered by the so-constructed tunnel arch.

Various methods of carrying out the invention are illustrated diagrammatically on 30 the accompanying drawings, in which:—

Figure 1 is a transverse section, showing on the right hand side an imaginary isometric view of the tunnel in course of construction.

Fig. 2 is an imaginary isometric view 35 showing a variation.

Fig. 3 is a transverse section, also showing on the right hand side an imaginary isometric view of the tunnel in course of 40 construction by a modified method, and

Fig. 4 is a corresponding fragmentary longitudinal section.

Figs. 5 and 6 are diagrammatic developed 45 plans illustrating alternative methods of longitudinal progress of a tunnel constructed by a method illustrated in Figs. 3 and 4.

Referring more particularly to Fig. 1:—
a is the outer profile of the tunnel which 50 is to be constructed, and b is the inner profile thereof.

The space between the profiles a and b is divided into sections, and small tunnels or headings c are driven along alternate sec-

tions as shown. However, the tunnels or 55 headings c may be separated by more than one intermediate section of the arch.

The excavated sections of the arch constituted by the headings c are then filled in with concrete or other suitable material, 60 as shown by the three top-most sections c at the crown of the arch.

After the concrete or other suitable material has been put in, the other sections d of the arched space between a and b, are 65 similarly excavated and filled in, so that eventually the complete arch of the tunnel becomes made in concrete or other suitable material *in situ* around the dumpling e.

Fig. 2 shows how a lateral heading f can 70 be run from one longitudinal heading c to another, thereby permitting one of these headings c to be filled in at the rear of f without interrupting communication with its leading face.

After the arch has been constructed and also if desired the side walls of the tunnel, the natural core or dumpling e is then excavated, and, if not already constructed on the above or any other system, and if required, the floor of the tunnel is then laid. 75

The filling of concrete or other suitable material of each section may be reinforced by steel or other rods or the like. These rods or the like may extend into the earth 80 or substance which occupies the spaces d on each sides of the spaces c, so as to connect with the concrete or other suitable material which is subsequently filled in the spaces d 85 after they have been excavated.

The method of tunneling and constructing a tunnel arch described above in connection with Figs. 1 and 2, involves driving the separated small tunnels or headings for the full length of the tunnel, before any part 90 of the tunnel arch can be completed.

Figs. 3-6 illustrate a method by which the arch space between a and b can be excavated and filled in in sections and the arch completed while the sectional tunnels are being 95 progressively advanced.

In these figures:—Small tunnels or headings g are driven at intervals around the arch space a—b. These headings g extend into the dumpling e to provide passages beneath the space for the arch or alongside the space for the side walls, during both excavation and after filling in. These headings g 100

are widened on one or both sides within the arch space $a-b$ in suitable length, and the excavated space between a and b is filled in with concrete or other suitable material.

5 When the filling has consolidated in the widened headings g , the adjoining headings g at that particular portion of the length of the tunnel can be widened and filled in, thus completing the arch.

10 The work can be carried out in various methods. For example, as illustrated by Fig. 5, which shows three sections of the arch marked respectively 1, 2, 3, all the headings g can be driven at approximately

15 the same rate of progress. The headings of sections 1 and 3 can then be widened and filled in in advance of the widening of section 2.

20 As obviously the headings g can be pushed forward at a more rapid rate than the widenings can be made and filled in, the headings may get so far ahead that widening can be carried out at situations longitudinally apart along the same heading. This is illustrated in Fig. 6, wherein the heading g of section 2 has been widened and filled in at a situation not adjoining the commencement of the tunnel. The filled-in portions of sections 1 and 3 may be assumed to be similarly detached filled-in widenings, or alternatively to be widenings extending from the mouth of the tunnel.

25 No matter what system of arranging the widenings is adopted, the extension of the headings into the dumplings provides passages beneath the arch for the removal of the excavated material, and for taking in the

concrete or other material for constructing the arch.

40 The remainder of the dumpling is eventually removed after the arch is completed, either after or before the entire tunnel is completed.

The concrete or other suitable filling may be reinforced as described in connection 45 with Figs. 1 and 2.

I claim:

1. A method of constructing a tunnel, consisting in excavating, longitudinally of the tunnel, sections around the space to be occupied by the tunnel arch, filling said excavated sections with concrete or other suitable material, said excavated sections being spaced around the arch so that when filled in the arch comprises a plurality of concrete 55 and earth portions arranged in alternation, and excavating and filling in the intermediate sections, prior to removing the dumpling.

2. A method of constructing a tunnel according to claim 1, in which said excavated sections extend into the dumpling to provide passages.

3. A method of constructing a tunnel according to claim 2, in which the separated 65 sections are separately internally widened and filled in.

In testimony whereof I have signed my name to this specification in the presence of two subscribing witnesses.

THOMAS MALCOLM McALPINE.
